[57] CLAIM

The ornamental design for a portion of a connector for
printed circuit boards, as shown and described.

DESCRIPTION

FIG. 1 is a top, front and left side perspective view of a
portion of a connector for printed circuit boards showing my
new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken line showing an additional fitting and the
remainder of the cord in FIG. 1 and the interior of the cord
in FIG. 7 is for illustrative purpose and forms no part of the
claimed design.
